FILTER PRESS

Heinrich Reitz, Bitterfeld, Germany, assignor to
 I. G. Farbenindustrie Aktiengesellschaft,
 Frankfort-on-the-Main, Germany

Application July 29, 1939, Serial No. 287,311
 In Germany November 16, 1931

3 Claims. (Cl. 100—50)

This invention relates to improvements in or relating to filter presses and more particularly to a combined filter and hydraulic press and is a continuation in part of my co-pending application, Serial No. 79,703, filed May 14, 1936, entitled "Filter press." Said application, Serial No. 79,703, is in turn a division of my application, Serial No. 642,725 which has since matured into U. S. Patent No. 2,048,352.

10 In the said co-pending application, Serial No. 642,725 I have described and claimed a filter press comprising a base, heads at opposite ends thereof rigidly secured to said base and provided with integral extensions thereon directed inwardly towards each other and in alignment, 15 collars in sliding and sealing engagement with the periphery of said extensions, the end face of each collar being adapted to be moved into sealing engagement with the inner face of the head, the collars being in alignment, hydraulically operated means operatively connected to each collar for reciprocating the same, a ram slidably and sealingly engaged with the inner surface of each collar to form therewith and 20 with the head a filtering chamber, hydraulically operated means positioned parallel to the first named hydraulic means and adapted to reciprocate the rams, filters mounted on the inner face of the extension and the outer face of the ram 25 in facing relations to each other, means for the entry of a primary fluid to said chamber and another means to permit exit of a secondary fluid, and means for operating the collar and the ram in proper sequence, said collar being moved over 30 said ram and then with the ram to release the press cake after a pressing operation has been completed.

The invention, the subject of the aforesaid co-pending application, thus provides for the simultaneous production of only one filter cake by each press plunger, whilst the present invention is adapted for the simultaneous production of two filter cakes by means of one and the same press plunger, and thus enables the output of 45 the filter press to be considerably increased. To this end, by way of modification of the invention, the subject of my co-pending application, each filtering chamber is divided into two compartments by means of an intermediate disk-shaped member, both ends of which are also designed as filtering surfaces. It is the purpose and object of this invention to provide a multi-compartment press of such construction.

In order more clearly to understand the invention reference is made to the accompanying

drawings which illustrate diagrammatically, and by way of example, an embodiment of a double-acting filter press in accordance therewith and in which:

Figure 1 is a longitudinal section with parts 5 broken away.

Figure 2 is a front elevation.

Figure 3 is a longitudinal partial section illustrating the press with the filtering chambers open. 10

Figure 4 is a longitudinal section, illustrating the positions of the moving parts at the end of the filtering operation, and

Figure 5 is a longitudinal partial section of a modification of the press. 15

On the drawings:

Reference numeral 1 designates the base of the press. The press is supplied at its opposite ends with heads 2 rigidly secured to the base. Tie rods 3 (shown broken away in Figure 1) unite 20 the press heads.

Centrally located in the press is the hydraulic press cylinder 4, in which there operate oppositely moving rams 5. Port 6 provides for supply and exhausting the working fluid for the 25 press cylinder.

Supported from and located above cylinder 4 is a smaller hydraulic cylinder 7. Cylinder 7 houses pistons 8 provided with connecting rods 9. Pistons 8 are moved on their outstroke by 30 fluid admitted through port 10, and on their instroke by fluid admitted through port 11. Each port is provided with conventional valve means (not disclosed). It will be appreciated that port 11 exhausts the working fluid, while working fluid 35 is being supplied through port 10 and vice versa.

Situated directly below cylinder 4 is another small hydraulic cylinder 12 which houses pistons 13. Pistons 13 are provided with connecting rods 14. Ports 14 and 15, functioning in the 40 same may as ports 10 and 11 of cylinder 7, are provided in cylinder 12. For reasons which will be subsequently understood, the effective surface of pistons 13 is less than the effective surface of pistons 8.

Each ram 5 has an extension 17 at its outer end. A rim or abutment 18 is provided at the inner end of each extension.

Each head 2 of the press is provided with an extension 19 facing a ram extension 17. The 50 ram and head extensions have the same circumference.

An intermediate member 20 is movably located between each ram and head. Each intermediate member is constructed with an enlarged central

portion 21 and outer portions 22 and 22a facing a ram extension 17 and a head extension 19 respectively. The circumference of the outer portions of each intermediate member is the same as that of the ram and head extensions. It will be appreciated that the construction so far described locates at each end of the press two filtering chambers I and II respectively, chamber I being formed between a ram extension 10 and an intermediate member, and chamber II between a head extension and an intermediate member.

The periphery of the so located filtering chambers is closed by collars 23 and 25, each collar 18 23 being movable on the ram extension and an outer portion 22 of an intermediate member, and each collar 25 being movable on a head extension and an outer portion 22a of an intermediate member. Each collar 23 is directly connected 20 to a connecting rod 9 by element 24. The movement of a piston 8 is therefore directly transmitted to a collar 23. On the other hand each collar 25 is directly connected to a connecting rod 16 by fastening means 25a. Here again the motion of a piston 13 is directly translated to a collar 25a.

There are provided near the lower end of the press guide rods 26. The rams, collars and intermediate members have carriages 27 fastened thereto, said carriages being slidable on said rods 26. Said rams, collars and intermediate members are accordingly supported and guided in their movement by said rods 26.

The face of each ram extension, of each outer portion of an intermediate member and of each head extension is provided with a filtering screen 28. Filtrate produced during the filtering action is discharged through ram extensions 17 by outlets 29, through intermediate members 20, by 40 outlets 29a, and through heads 19 by outlets 29b.

Each head 2 is centrally apertured at 30 to provide a passage for feeding fluid to filtering chamber II. On the other hand, each intermediate member is centrally apertured at 31 to provide 45 means for egress of fluid from filtering chamber II to filtering chamber I. Fluid is supplied to passages 30 by inlets 32.

The supply of the medium to be filtered is controlled by the hydraulically operated controls 30a. 50 Each control comprises a hydraulic cylinder 35 in which a piston 36 operates. 37 and 38 represent hydraulic fluid inlets and outlets for the cylinder. Piston 36 has a connecting rod 34 which extends through passage 30 and has attached to its other end an ordinary piston valve 33. Valve 33 is seated in the aperture 33a, leading to filtering chamber II. When pressure is exerted on piston 36 by fluid admitted through port 37, valve 33 is unseated, whereupon the medium to be filtered 60 feeds from passage 30 to chamber II and by way of passage 31 to chamber I. Subsequently when pressure is exerted on the piston by hydraulic fluid admitted through port 38, valve 33 is again seated in aperture 33a.

65 Considering only one end of the press for the sake of simplicity, the operation of the press will now be described. Let it be assumed that the press is in the position shown in Figure 3, with ram 5 retracted into the press cylinder 4, collar 23 drawn over ram extension 17 and into engagement with rim 18, collar 25 resting on extension 19 of head 2 in contact with the abutting wall thereof, and intermediate member 20 positioned midway between extension 19 of head 2 and extension 17 of ram 5. In this position both filter-

ing chambers I and II are freely accessible. It will be understood that at this point piston 8 is at the end of its instroke, and piston 13 at the end of its outstroke. Port 10 of cylinder 7 is now opened for fluid supply and port 11 for fluid discharge. Piston 8 is thereby caused to move toward the head causing collar 23 to move in that direction until it slides over the outer portion 22 of the intermediate member and contacts with the enlarged central portion 21 of said intermediate member. At the same time port 15 of cylinder 12 is opened for fluid supply and port 14 for fluid discharge. Piston 13 is thus caused to retract and collar 25 to move inwardly on head extension 19 toward the outer portion 22a of the 15 intermediate member. Further movement of piston 8 results in a movement of the intermediate member and collars 22 and 25 as a unit. Movement of collar 25 outwardly as a result of the motion imparted by piston 8 is possible because of the larger effective surface of piston 8. During the further movement of piston 8, ram 5 is operated in the same direction. The press parts will thus have assumed the position shown in Figure 1, with filtering chambers I and II 25 clearly defined. When this position has been attained, control 30a is operated to permit the medium to be filtered to feed through inlet 32, passage 30 and aperture 33a, into filtering chamber II, and through aperture 31 into filtering chamber I. Control 30a is shut off when the filtering chambers are filled. Hydraulic fluid is then fed to press cylinder 4 to operate ram 5 which moves the assembled parts to the right as a unit, causing compression of the material in the 35 filtering chambers. The filtrate produced issues through the outlets 29, 29a and 29b. At this point the parts are in the position clearly illustrated in Figure 4. a 40

When filtration is completed, the opening of the press is inaugurated by releasing the pressure on ram 5. Fluid is supplied through port 15 of cylinder 12, to further retract piston 13 and effect retrograde movement of collar 25, and thus also of intermediate member 20, collar 23 45 and ram 5. Piston 8 is then retracted by admission of fluid through port 11, whereby collar 23 is moved out of engagement with the central portion 21 of intermediate member 20 and over extension 17 of the ram, while contact is effected between the collar and rim 18 of the ram extension. At the same time the movement of piston 13 is reversed so as to move collar 25 over the extension 19 of head 2 into engagement with the 55 abutting wall of said head. Further retraction of collar 23 through retraction of piston 8 causes the ram to move further into cylinder 4. As a result of this disposition of the collars and ram, both press cakes are freely accessible and can be 60 removed. The press has then returned to its initial position as illustrated in Figure 3.

It is to be understood that the mode of operation herein outlined is purely illustrative, since because of the structure possessed by the press, 65 it is possible to open and close the press by a different sequence of steps than that described. Thus, for instance, in closing the press instead of first positively actuating piston 8 and collar 23 to the position of Figure 1, ram 5 may be first operated to the position of Figure 1 and piston 8 and collar 23 then moved to the desired position. Again in opening the press, pistons 8 and 13 may be operated simultaneously. As a further alternative instead of first retracting piston 13 and 75

then retracting piston 8, piston 8 may be first retracted to engage with rim 18, and then further moved to retract the ram and expose the filter cake in chamber I for removal. Thereafter, piston 13 may be retracted so as to disengage member 20 from the filter cake in chamber II, whereupon by reversing the movement of piston 13, so as to push collar 25 over extension 19 and into engagement with the abutting wall of the head, the filter cake in chamber II is freely exposed for removal.

Figure 5 illustrates a modified form of the invention. In this modification in lieu of cylinder 12, two cylinders 12a are provided, each located adjacent a head and in alignment with cylinder 7. It will be apparent that in this modification the operation will be the same as that described, except that the movements of piston 13a will be reversed. Thus to position collar 25 so as to form filtering chamber II, piston 13a is moved forward instead of retracted. The same is true in moving intermediate member 20 to disengage it from the filter cake. On the other hand, piston 13 is retracted in moving collar 25 over the head extension to open the press.

It will be apparent that the construction of the filter press according to the present invention allows of a variety of modes of operation and the appended claims while describing such operation in general terms are not to be construed as limited to any particular mode herein described.

I claim:

1. In a hydraulic press a base, a head fixed to one end of said base, a hydraulic cylinder disposed inwardly from and co-axial with said head, a ram in said cylinder, press means intermediate said head and hydraulic cylinder consisting of an extension on said head having its face disposed toward said ram, a disk-shaped member 40 having a central portion of greater diameter than

said head extension and outer portions of the same diameter as said head extension, a collar located between said head and said disk-shaped member, adapted to slidably and sealingly engage with said head extension and the periphery 5 of the adjacent outer portion of said disk-shaped member and to sealingly engage with its end face said central portion of said disk-shaped member, a second collar between said ram and said disk-shaped member similar to the first, 10 adapted to slidably and sealingly engage with said ram and the other outer portion of said disk-shaped member and to sealingly engage with its end face said central portion of said disk-shaped member, a second hydraulic cylinder, a 15 piston in said second cylinder fixedly secured only to said second collar, a third hydraulic cylinder, a piston in said third cylinder fixedly secured only to said other collar, filters mounted on both faces of said disk-shaped member and 20 on the face of the extension of said head and of said ram, respectively, so as to form in conjunction with the head extension, said collars, said disk-shaped member and said ram, filtering chambers, means for the entry of a primary fluid 25 to said chambers and other means to permit exit of a secondary fluid therefrom, the aforesaid elements being adapted to operate in such a manner that in forming and opening said filtering chambers movement of said disk-shaped 30 member is exclusively caused by the movements of the pistons directly controlling the movements of said first and second collars.

2. The device defined in claim 1 wherein means are provided for guiding the ram, collars and 35 disk-shaped member when in motion.

3. The device defined in claim 1 wherein the disk-shaped member is provided with an opening which connects the filtering chambers.

HEINRICH REITZ. 40
